ATTACHMENT FOR A PORTABLE DRIER

Hec Barth, Chicago, Ill.

Application May 1, 1956, Serial No. 41,286

Term of patent 14 years

(Cl. D86—10)

FIG. 1

FIG. 2

FIG. 3

FIG. 4

FIG. 5

FIG. 6

FIG. 7

Figure 1 is a perspective view of an attachment for a portable drier showing my new design with the dotted lines being used for illustrative purposes only.

Figure 2 is a side elevational view thereof;

Figure 3 is an outer end view thereof;

Figure 4 is an inner end view thereof;

Figure 5 is a top view thereof;

Figure 6 is a bottom view thereof; and

Figure 7 is a top plan view thereof showing the attachment in open position.

I claim:

The ornamental design for an attachment for a portable drier, as shown and described.
